POWDERED MATERIAL DISPENSER

Marc H. Sessions, Los Angeles, Calif., assignor to United States Borax & Chemical Corporation, Los Angeles, Calif., a corporation of Nevada

Filed Apr. 25, 1963, Ser. No. 74,623

Term of patent 14 years

(Cl. D4—3)

FIG. 1 is a front view of a powdered material dispenser, showing my new design;

FIG. 2 is a side view thereof; and

FIG. 3 is a perspective view thereof.

The rear is flat and plain.

I claim:

The ornamental design for a powdered material dispenser, as shown and described.
